Emery, Barth, Jernigan & Tracy

UNITED STATES PATENT OFFICE.

WALTER L. FRY, OF DETROIT, MICHIGAN, ASSIGNOR TO SPRINGFIELD BODY CORPORATION OF NEW YORK, OF NEW YORK, N. Y., A CORPORATION OF NEW YORK.

ANTIRATTLES.

1,253,582.

Specification of Letters Patent. Patented Jan. 15, 1918.

Application filed February 16, 1917. Serial No. 148,938.

To all whom it may concern:

Be it known that I, WALTER L. FRY, a citizen of the United States, a resident of the city of Detroit, county of Wayne, and State of Michigan, have invented an Improvement in Antirattlers, of which the following is a specification.

My invention relates to anti-rattlers, adapted for use in connection with the doors or windows or other hinged or removable portions of vehicle bodies, and particularly to automobile bodies. In automobile bodies, the hinged or removable portions are particularly likely to become loosened and to rattle by reason of the severe jolting the body receives due to the movement of the vehicle, and by reason of the movement of the parts of the body with respect to one another incident to the twisting stresses applied to the frame upon which the body is mounted, and to other causes.

Some of the objects of my invention are to properly locate or position the anti-rattlers upon the hinged door or window or other movable member of a body, so that they may exert their action in the most effective manner and to provide an anti-rattler of simple construction, wherein the buffer element is completely protected against abrasion. My invention also aims to provide a suitable buffer for the corner of a door or window, which will act upon two edges of the door or window in the plane of the door or upon two edges of the door and window, and in addition thereto, upon the inside of the door at right angles to the plane of the door. Other objects of my invention will be pointed out in the following specification.

I have discovered that anti-rattling means, in order to be most effective should be so constructed and arranged as to exert their action in the plane of the door, although such anti-rattling means may be supplemented by anti-rattlers exerting their action in a direction perpendicular to the plane of the door. I have also found that the anti-rattlers which exert their pressure in the plane of the door should be placed at certain positions in order to most effectively cushion the shocks. It will be understood, however, that my improved anti-rattler is not limited to use in any particular place,

and that it may be applied in other places if desired.

In the drawings, Figure 1 is a side view of an automobile door indicating the positions at which the anti-rattlers should be placed; Fig. 2 is a sectional view of a form of my improved anti-rattler particularly adapted for use at the corner of the door; Fig. 3 is an end view of the anti-rattler shown in Fig. 2, partly broken away in order to show the position of the parts; Fig. 4 is a perspective view of another modification of my invention and Fig. 5 is a sectional view of the modification shown in Fig. 4.

Fig. 1 may be taken to represent either a full door, including a window frame such as is used in a brougham or limousine, or a half door, such as is used on the ordinary touring car. If the drawing is taken to represent the latter, portions lying above the line A—B may be disregarded. Considering Fig. 1 to represent the half door, and disregarding such portions of the drawing as lie above the line A—B, 1 represents the door which is hinged at one edge by means of the hinges 2—2. The positions of the anti-rattlers are indicated at 3, 4 and 5. The anti-rattler 3 is placed upon a door member so as to act upon the unhinged edge of the door at a point adjacent to its upper edge 6, and in the plane thereof. Anti-rattler 4 is placed upon a door member so as to act upon the unhinged edge of the door at a point adjacent to its bottom. Anti-rattler 5 is placed upon a door member so as to exert its action upon the bottom edge of the door in the plane thereof, at a point adjacent the unhinged edge.

It will be obvious that the anti-rattlers may be placed upon the door post, door sill, door rail, door stile or the door stop, and I therefore do not wish to limit myself to placing said anti-rattlers upon any one of said door members.

If desired, anti-rattlers 4 and 5 may be combined in a unitary construction, such as is illustrated in Figs. 2, 3, 4 and 5.

Considering Fig. 1 as a drawing of a full door, such as is used in limousines and the like, the points of application of the anti-rattlers are shown at 3', 4, 5 and 5'. In such a construction the door is hinged by means

of hinges 2, 2 and 2', and anti-rattlers 4 and 5 occupy the same positions as they would in the case of a half door. Anti-rattler 3, however, is omitted or moved to position 3', that being so as to act upon the unhinged edge of the door in the plane thereof, adjacent to its upper edge. Anti-rattler 5' occupies a position corresponding to anti-rattler 5, acting upon the upper edge of the door in the plane thereof and adjacent to the unhinged edge.

I have found that the points at which the anti-rattlers are placed according to my invention, are the points of first impact for the various conditions of looseness of the door from which rattling proceeds. Thus, considering Fig. 1 as a half door and disregarding the portions of the drawing lying above the line A—B, it will be seen that if the upper hinge loosens, the door will fall away to the left at the top and will first strike the door post at or about the point 3. On the other hand, if the lower hinge becomes loosened, the door may fly upward and thus first strike the post at or about the point 4. If the whole door be loosened and sag or if the upper hinge become loosened and there is sufficient clearance between the door and the door post, the door will first strike at or about the point 5.

Considering the drawing as an illustration of a full door, it will be seen that if the upper hinge or hinges loosen, the door will first strike at or about the point of 3'. If the lower hinge or hinges loosen, the door may fly upward and strike at or about the point 4. If the whole door be moved bodily downward, due to looseness of the hinges, the door will first strike at or about the point 5 or if it be moved upward, at or about the point 5'.

I thus provide anti-rattlers at points of first impact instead of at points somewhat removed therefrom, as is the present practice, and it will be noted that I make no attempt whatever to hold the door in position by means of the anti-rattlers, but permit the door to make such movements as it will, under the conditions of operations. Any attempt to hold the door in position simply results in the loosening of the hinges and consequently an aggravating of the conditions producing rattling, whereas, if the door be permitted to move, the effort being simply to absorb the shock incident to such movement, the door will always remain hung from the hinges and the hinges will consequently remain tight for a longer time.

My improved anti-rattler consists primarily of two members, one of which, the buffer member, is made of resilient material and the other of which is made of metal or other suitable material adapted to resist wear.

In Fig. 2 I have illustrated a form of my

invention applicable to the corner of a door and designed to absorb shocks occurring at an angle to one another and in the plane of the door. Such a construction may be conveniently used at the points 4—5 of Fig. 1. The embodiment shown in Fig. 2 consists of the buffer member 7 mounted in a recess formed at the corner of the door, which buffer member is supplied with a pair of wear plates 14 and 15 located at an angle of one another. Bearing upon the wear plates are a pair of plungers 16 and 17 which are connected by a metallic shoe 18. In this modification, if pressure is produced at the point 4, the plunger 16 will move inwardly, thus depressing wear plate 14 and compressing buffer 7. Plunger 17, during this time, will slide longitudinally of the wear plate 15, such movement being permitted by the slot in the casting 19. On the other hand, if pressure is produced at the point 5, plunger 17 will move inwardly thus compressing buffer 7 and causing plunger 16 to move along wear plate 14 through the slot provided for this purpose. Both actions, however, may occur at the same time, and both plungers may be, to a slight extent, simultaneously moved along their respective wear plates, and caused to bring pressure to bear upon the buffer 7. The entire anti-rattler may be conveniently attached to the corner of the door by means of screws 20 or in any other suitable manner.

In Figs. 4 and 5 I have shown a modification of my invention adapted for use at the corner of the door when it is desired to exert an action both in the plane of the door and in a plane at right angles thereto. This modification provides for the cushioning of shocks at the points 4 and 5 of shocks occurring between the inside of the door and the door stop. It consists of the buffer member 7 which may be conveniently formed in the shape of a cube set into the lower inside corner of the door at its unhinged edge, and a protective plate 21, which surrounds the corner of the door on three sides. Protective plate 21 may be held in position by any suitable means, such as by attaching it to the rubber buffer 7 and fastening the latter in position, or by means of a pin 22 fastened to the door rail and passing through a hole 23 in the protecting plate. Hole 23 is made large enough so that movement of the plate 21 may occur, but when the anti-rattler is in the inoperative position the pin 22 rests against the edge of the hole 23. As shown in Fig. 5, the underside of plate 21 is slightly beveled to ride up upon the door sill 8 and when the door is closed, the anti-rattler will not only make contact with the door sill 8 but also with the door stop 24, and the door post (not shown).

I do not intend to confine myself to the modifications shown and described, since

they may be greatly varied without departing from the spirit of my invention.

What I claim is:

1. In a device of the kind described, a door sill, a door post located at an angle to the door sill, a movable door, a block of resilient material carried by the door and a metallic protective member mounted upon the block of resilient material and adapted to contact with the door sill and the door post.
2. In a device of the kind described, a door sill, a door post and a door stop, a movable door member coöperating therewith and cushioning means interposed between the door sill, the door post and the door stop and the movable door member.
3. In a device of the kind described, a plurality of stationary door members, com-

prising a door sill, a door post and a door stop, a movable door member and a block of resilient material carried by the movable door member and adapted to contact with the three stationary door members.

4. In a device of the kind described, a plurality of stationary door members, comprising a door sill, a door post and a door stop, a movable door member, a block of resilient material carried by the movable door member at the inner lower corner of the unhinged edge thereof and a metallic protective plate mounted upon the block of resilient material and adapted to contact with the stationary door members.

In testimony whereof, I have signed my name to this specification this thirteenth day of February, 1917.

WALTER L. FRY
